UNITED STATES PATENT OFFICE

CHESTER H. BRASELTON, OF NEW YORK, N. Y.

INERTIA OPERATED PUMP MECHANISM

Application filed June 6, 1922. Serial No. 566,379.

This invention relates to inertia operated pump mechanism of the type wherein the relative movement of the piston and cylinder of the pump caused by the inertia of the piston will induce a pumping action for fluid. Particularly the invention relates to such mechanism as employed for elevating a liquid, such as gasoline used in motor cars, from a lower or main reservoir to a higher auxiliary reservoir from which it may feed down to a carburetor or other liquid distributing device for use in the engine of the machine.

Among the objects of this invention is to devise an inertia operated mechanism which is adapted for fixture upon the frame or body of any automobile or other vehicle in which the frictional connection between the relatively movable elements is reduced to a minimum, thereby permitting as small a weight as is absolutely essential in order to secure the pumping effect in the mechanism. This object is obtained chiefly by providing a single bearing surface between the plunger element and the support affixed to the base of the container, this connection being slideable and of such a length as to prevent binding of the interrelated parts and dispensing with the necessity of a two contact bearing.

Another object of the invention is to provide novel means for making the pump action ineffective after the container has received liquid up to a predetermined level. Upon the filling of the container up to this limit, the pump cylinder is automatically held open to the atmosphere and thus the intermittent movement thereof has no effect in causing a movement of liquid from the main or reservoir tank up to the auxiliary tank, but merely an idle movement doing no work.

It is an object also to prevent extreme pumping action when the mechanism is subjected to abnormally powerful forces such as would occur when the vehicle is passing over an extremely rough road. This object is obtained by providing a resilient device which is adapted to dampen the movement of the plunger when such movement occurs beyond a certain limit determined by the design of the pump, the resilient element also provid-

ing a quick return for the plunger from the outer limit of this movement.

The invention also relates to novel features of the valvular construction, the connection between the interrelated parts, and to various mechanical features of design and operation which will more fully hereinafter appear by reference to the accompanying drawings, forming a part of this specification, and, in which

Figure I is a conventional showing of an automobile with my invention applied thereto;

Figure II is a detailed sectional elevation of the auxiliary pump mechanism and tank showing the various novel features of the invention;

Figure III is a cross sectional elevation taken of the upper float controlled valve mechanism taken at an angle of 90° from the point of view shown in Figure II;

Figure IV is a detailed plan view of the upper valve structure taken on line 4—4 of Figure II, and

Figure V is a detailed sectional view taken on line 5—5 of Figure II.

In the various sectional views the viewpoint is taken in the direction of the small arrows affixed to the drawings.

In Figure I of the drawings, there is shown a conventional form of automobile 1, having an engine 2, fed by a carburetor 3, receiving fuel through pipe 4 from the auxiliary tank supply 5, positioned on the dash 6'. The main supply of fuel is in the rear reservoir tank 5' connected to the auxiliary tank 5 by means of a conduit or pipe 8. The pumping mechanism operative to raise the liquid fuel in the tank 5' to a height in the tank 5, from which it may feed by gravity to the carburetor, is shown attached to the dash, but it should be understood that any other part of the engine or automobile body would serve the same purpose in this system, inasmuch as the principle as involved in the operation of the tank is dependent upon the vibration of the tank 5, and, this vibration in an automobile is secured by fastening the tank to any part of the frame or engine.

In Figure II there is shown the pump

mechanism in detail together with the auxiliary tank receptacle associated therewith. The tank is shown in the form of a main cylindrical portion 6, having end pieces 7 and 8' formed of pressed metal and, in the case of the bottom piece 8', permanently fixed thereto by solder or other means, and, in the case of the upper plate 7, attached by means of screws 9 which bind together the flange member 10 of the cap 7, and the flange 11 secured to the upper part of the cylinder, said screws passing through an interposed gasket member 12, thereby obtaining a fluid tight joint.

The base of the tank 8' has two apertures formed therein, the aperture 12 having a fitting 13 secured thereto, adapted to connect the outlet pipe 4 to the tank. In the center of the plate 8', there is a second aperture in which a pipe 14 is affixed by means of solder or some other means making a fluid tight joint, the ends of the pipe extending below the end cap to a point which will permit of the attachment thereto of a screw threaded element 15, to which is attached a fitting 16 terminating in a screw threaded aperture 17 adapted to connect the inlet pipe 8 extending from the main tank 5'. The fitting 16 is hollowed to permit the insertion of a deflector plate 18 adapted to be positioned immediately above the inlet aperture at the base thereof and a cylindrical screen 19 extending from the edges of the deflector plate up to the base of the pipe 14 so that a liquid strainer of relatively large proportions is provided. Adjacent the base of the tank, a support plate 20 having openings 20' is provided, being fixed to the interior of the casing by solder or other means and formed with an upper conical projection adapted to receive a coupling member 21, which member connects the pipe 14, at its upper end, to the cylinder 22 of the pump. At the junction of the cylinder 22 and pipe 14, there is positioned a bushing 23, the lower edge of which is formed into an annular flange 24, adapted to rest on a shoulder 25 of the coupling 21, this joint being made liquid tight by means of an annular washer 26 placed between the lower edge of the annular flange and the shoulder 25. The lower end of the bushing has an opening somewhat relatively constricted, the upper portion of the bushing having an enlarged opening, thus forming a shoulder interiorly of the bushing and positioned partway up the length thereof. Upon this inner shoulder 27, a drop plate valve 28 is adapted to function, the exact form of the valve being clearly brought out in Figure V of the drawings, there being four radial projections on the circumference of the valve which are adapted to engage the interior walls of the bushing and have longitudinal movements therewith. The upward movement of the valve is limited by the base of

a pipe tubing 29, which has a circumferential ring 30 resting upon shoulder 32 formed on the upper interior wall of the bushing 23, the upper end of the tubing 29 terminating a short distance upwardly within the cylinder 22.

The elements described, constitute the stationary portions of the pump and tank. The movable elements are comprised in a plunger proper 40 movable axially within the cylinder 22, and an inertia element 41, a valve 42 and a float 60 adapted to control the movement of said valve. The plunger 40 is in the shape of a tube, having an enlarged cavity at its base adjacent the upwardly extending pipe 29 and extending below the top thereof, the lower portion of the plunger moving in the recess formed by the pipe 29 and the wall of the cylinder. The upper end of the plunger 40 is somewhat constricted and carries on its upper terminal a flat plate 44 having four radial projections at approximately 90° around the circumference thereof which projections are adapted to ride in vertical run-ways 45 formed in a cage 46 immediately above the upper end of the plunger 40. This cage has its side walls secured to an annular plate 47 which is screw-threaded to a part adjacent the upper terminus of the plunger, the outer edge of this plate carrying machine screws 47' which are adapted to enter pockets 47" secured in the end of a hollow cylindrical mass 48, completely surrounding the pump and plunger elements. The upper center of the cage 46 receives an eye bolt 49 to which is secured a chain 50, the upper end of the chain being operated by means of a flexible rod 51 and ring 52 working through the arcuate tube 53 whereby the plunger element may be worked manually from without the casing.

To the upper end of the eye bolt 49 is fixed an annular stamping 54 having a downward turned flange 55, the base of said annular plate bearing upon the upper end of the main coil supporting spring 56, the lower end of said spring resting around the base of the conical support 20 adjacent the lower end of the casing.

Adapted to rest upon the upper surface of the inertia element 48 is a float 60 of annular formation and with a hollow interior such as will permit axial movement thereof about the eye bolt 49. By means of bolts 61, plates 62 are secured to the base of the float, these plates projecting inwardly to a point adjacent the upper periphery of the plunger element immediately below the valve plate 42 so that when the float is raised by liquid or manual means, the inner end of these plates 62 engage the valve and lift it off its seat thereby rendering the movement of the plunger 40 entirely ineffective as a pumping element. By this means when the tank is filled with liquid to a predetermined point, the

pump, even though its movement continues, fails to add additional liquid to the tank.

About mid-way around the wall of the cylinder 22 and between said wall and the inner wall of the inertia element 48, is fixed a ring 65, which ring serves as a lower supporting base of the coil spring 66 surrounding the cylinder and extending above the top thereof, the end of the spring being free. The object 10 of this spring is to prevent a too-vigorous downward movement of the plunger in the event that it is subjected to severe external forces. Ordinarily, the top of the spring is free, and does not contact against the supporting plate 47 at the top of the plunger, the movement of said plunger within said normal ranges being unobstructed. But in the event that a severe force is placed upon the plunger, and causing it to move downwardly 15 to an abnormal extent, this plate will contact with the top of the spring, which thereby absorbs the energy of the movement, brings the plunger to a state of rest, followed by a consequent quick reactive effect tending to 20 restore the plunger to its normal position again.

As previously intimated, the operation of the pumping mechanism above described is dependent upon the relative movement of a 30 floating or freely movable member having a relatively high mass, and, consequently, high inertia effect, and a member such as the cylinder of the pump, fixed to the support, and susceptible of quick movement such as cannot be followed by the inertia element. Consequently, when there is such a movement of the support, there occurs a relative movement between the plunger element and the cylinder element, resulting in a compression 35 of the fluid in the pump chamber, which compression is followed by an expansion due to the action of the compression spring 56. In the case where the support is part of an automobile, it is readily understood that the 40 constant vibration and movement of the frame of the automobile over a road results in a continued movement of the cylinder rigidly attached to the frame, in conjunction with the vibration due to the engine itself, and thus there results a constant relative 45 movement of the cylinder and plunger inducing in conjunction with the one way movement of the inlet and outlet valves a constant flow of liquid or fuel from the main tank of the automobile to the auxiliary tank 5, the liquid then feeding down through the pipe 4 into the carburetor and then into the engine itself. This pumping action is continuous 50 while the engine is in operation or the car is in movement, and, consequently, if the fuel is not being used very rapidly, the supply in the auxiliary tank 5 will increase to a point 55 when the liquid level will support the float 60 thereby lifting the valve 42 from its seat, destroying the suction effect of the pump, and

permitting the same to idle without doing any work. This idling of the pump continues until the liquid level is lowered to a point where the float may again permit the valve to reseat itself and the pumping action goes 65 once more into effect.

Should the auxiliary tank 5 be entirely empty at the time of starting, by means of the ring 52 and its connecting members 51 and 50, the plunger element may be reciprocated 70 so that a pumping action may, in this manner, manually be carried on, and an initial supply of fuel brought up into the auxiliary tank. After starting of the engine, the supply will be automatically taken care of by the engine 75 and automobile vibration. Attention is directed to the construction particularly of the float element, which is in the shape of an annular ring surrounding the central axis of the tank, whereby a balanced distribution of 80 weight is secured in the tank. This arrangement also permits a novel mounting of the pumping mechanism so that all the weight is supported from the central base member 20 without the necessity of utilizing a guide 85 bearing secured to the upper top plate of the tank. This mounting is improved also by means of the long bearing contact between the plunger 40 and the cylinder 22, this bearing tending to prevent a lateral warping of 90 the plunger and inertia mass as a unit. The above arrangement of the pumping mechanism forms an exceedingly well balanced and unified construction, permitting smooth and efficient movement and resulting in economy 95 of weight and power requisite for the pumping operation.

It is understood, of course, that the embodiment of the invention above disclosed is 100 illustrative rather than definitive and thus the scope of the invention is bounded only by the scope of the claims hereto appended, such claims being intended to cover all objects of the modification coming within their terminality.

Having thus described my invention, what I desire to claim is as follows:

What I claim is:

1. In a device of the class described, the combination of a tank, means adapted to lift liquid and discharge it into said tank, and including a plunger, a weight operatively connected to said plunger and adapted to move the same when said weight is moved, a delivery conduit leading from said means to said tank, and float controlled means adapted to render said first mentioned means inoperative when the liquid supply in the tank reaches a predetermined level, said float controlled means being carried by said plunger.

2. In a device of the class described, the combination of a tank, a cylinder supported therein, a hollow plunger reciprocatably mounted in said cylinder and having a valve 105

seat at its upper end, a weight supported by said plunger below said valve seat, a discharge valve cooperating with said valve seat, a float surrounding said valve seat above said weight and provided with means for engaging said discharge valve, and means for resiliently supporting said weight.

3. In a device of the class described, the combination of a tank, a cylinder supported therein, a plunger reciprocatably mounted in said cylinder, a plate secured to the upper end of said plunger, a weight secured to said plate and surrounding the cylinder leaving an annular space between said weight and cylinder, resilient means for supporting said weight, a stop ring on the outer wall of said cylinder, and a spring engaging said stop ring and positioned in the annular space between said cylinder and weight to restrain excessive movements of said plunger.

4. In a device of the class described, the combination of a tank, a cylinder supported therein, a plunger reciprocatably mounted in said cylinder, a weight secured to the upper end of said plunger, means for resiliently supporting said weight, an intake valve and a discharge valve cooperating with said cylinder and plunger to introduce liquid into the tank, means secured to the tank forming the sole support for said cylinder and plunger, and means actuated by the fluid level in the tank when said level reaches a predetermined maximum for engaging one of said valves and lifting the same off of its seat to render the cylinder and plunger inoperative to introduce liquid into the tank, said means including a member adapted to contact with said liquid.

5. In a device of the class described, the combination of a tank, a cylinder axially supported therein, a plunger reciprocatably mounted in the cylinder, a weight secured to the upper end of the plunger, means for resiliently supporting said weight, an intake valve and a discharge valve cooperating with said cylinder and plunger to permit introduction of fluid into the tank, said weight and plunger being guided solely by the cylinder, said cylinder being supported at its lower end only from the tank, and means operable by the liquid level when the same reaches a predetermined maximum for engaging said discharge valve to lift the same from its seat and render said cylinder and plunger inoperative to introduce fluid into the tank, said means including a member adapted to contact with said fluid.

6. In a device of the class described, the combination of a tank, a cylinder supported therein, a weighted plunger reciprocatably mounted in said cylinder, an intake valve and a discharge valve for controlling the flow of liquid into said cylinder and from said cylinder to said tank, and means including a member normally moving with said plunger

for rendering one of said valves ineffective when the liquid reaches a predetermined level in the tank.

7. In a device of the class described, the combination of a tank, a cylinder supported therein, a weighted hollow plunger reciprocatably mounted in said cylinder and having a discharge check valve therein, and means for rendering said discharge check valve ineffective when the liquid level in the tank rises to a predetermined level including a float mounted on the upper end of the hollow plunger so that it is normally supported thereby but may move upwardly with respect thereto, and connections whereby said float acts on said discharge check valve.

8. In a device of the class described the combination of a tank, an inertia actuated pump discharging into said tank, and means for rendering said pump inoperative for a portion of the stroke thereof when the liquid in said tank reaches a predetermined level and for increasing the inoperative portion of the stroke as the level of the liquid thereafter rises until said pump becomes completely inoperative at a predetermined maximum level.

In testimony whereof, I affix my signature.

CHESTER H. BRASELTON.
